UNITED STATES PATENT OFFICE.

PAUL EGEDI, OF BUFFALO, NEW YORK.

WATER-MOTOR.

1,352,588.

Specification of Letters Patent. Patented Sept. 14, 1920.

Application filed October 24, 1919. Serial No. 333,032.

To all whom it may concern:

Be it known that I, PAUL EGEDI, a citizen of Hungary, and a resident of Buffalo, in the county of Erie and State of New York, have invented certain new and useful Improvements in Water-Motors, of which the following is a specification.

The present invention relates to water motors of the rotary type.

One of the objects of the invention is to provide a motor, which is adapted to be attached to a water faucet, thus rendering its use possible for running light machinery in dwellings, etc., not supplied with electric power.

Another object of the invention is to provide a motor with a gearing, the driven shaft of which may be shifted to any desired position in relation to the wall or other support, adjacent to which the motor is attached to the faucet.

A further object of the invention is to produce a motor of the type described, which is simple in construction, efficient in operation and which can be manufactured on a commercial scale or, in other words, one which is not so difficult to make as to be beyond the reasonable cost of such a device.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction, within the scope of the appended claims without departing from the spirit or sacrificing any of the advantages of the invention.

One of the many possible embodiments of the invention is illustrated in the accompanying drawings, in which:

Figure 1 is a side elevation, partly in section, of a motor constructed in accordance with the present invention; Fig. 2 is a similar elevation, on a larger scale; Fig. 3 is a section taken on line 3-3 of Fig. 2; Fig. 4 is a perspective view of a portion of the rotor; Fig. 5 is a perspective view of a housing covering the gearing of the motor; Fig. 6 is a perspective view of an element for detachably fastening the housing to the motor casing; and Fig. 7 is a perspective

view of the bearing of the driven shaft of the motor.

In the drawings, the numeral 10 indicates the motor casing, including a section 11 that is substantially circular in cross-section. This casing may be made of any suitable material, in the case illustrated in the drawings of sheet metal, comprising a plurality of sections which are united in the usual manner. From the circular section 11 of the casing rises tangentially a nipple 12, into which fits the outlet of a faucet 13, a gasket 14, of rubber or similar material, being interposed to prevent leakage of water at this point. The casing is provided, preferably, at its lowest portion with an outlet opening 15, through which the water is discharged into the sink, on which the faucet is mounted, or into any receptacle connected with a waste-pipe or sewer. In order to properly support the motor upon the faucet, there are attached to or made integral with the casing upwardly projecting clamping members 16, which are adapted to be brought into engagement with the faucet pipe and held thereagainst by a bolt 17 and clamping nut 18.

To the opposite outer faces of the circular portion of the casing are centrally secured bearings 19, in which is rotatably journaled a shaft 20, carrying a rotor 21. This rotor is disposed within the casing and comprises two disks 22, the peripheral portions of which are connected by blades 23. The disks are fixed, for instance by rivets 24, to a hub 25, that is drawn over the shaft 20 and secured thereto in any suitable manner, for instance by a pin 26. One end of the rotor shaft extends outside of the casing and carries at that end a bevel gear 27, in mesh with a similar gear 28, the latter being mounted upon a driven shaft 29, that extends at right angles to the shaft 20. The shaft 29 is journaled in a bearing block 30, shown in detail in Fig. 7 of the drawings. The inner end of this block is split, as shown at 31, and provided with an arc-shaped dove-tailed groove 32, into which fits the arc-shaped dove-tailed extension 33 of a support 34, the latter being riveted or otherwise fixed to that outer face of the casing which is adjacent the bevel gear 27. A clamping screw 35, extending through the split portion of the bearing block 30, serves to fix the position of the latter upon the support 34. The center of the arc of the dove-tailed extension

33 coincides with the center of the rotor shaft 20, thereby permitting the driven shaft 29 to be swung around the shaft 20 to any desired position.

5 The gears 27, 28 and the bearing block 30 are covered by a housing 36, that is detachably held upon the motor casing by clamping members 37, shown in detail in Fig. 6 of the drawings. The driven shaft 10 29 extends through an arc-shaped slot 38 in said housing, permitting the said shaft to be shifted around the rotor shaft 20.

The operation of the invention is obvious from the foregoing description. In placing the motor upon the faucet, first the latter is inserted into the nipple 12 and then the clamping members 16 brought into engagement with the faucet pipe. The driven shaft 20 is then adjusted in relation to the wall, upon which the faucet is mounted, by detaching the housing 36, unscrewing the clamping screw 35, and shifting the bearing block 30 to the desired position upon the support 34. After this, the screw 35 is brought 25 to clamping position and the housing mounted upon the motor casing. When the motor has been adjusted in place, the faucet is opened, the water, flowing down through the nipple 12, impinging upon the blades of the 30 rotor, thereby actuating the latter.

The motor casing, rotor and housing are very light in construction, thus particularly fitting it for the use described. Obviously, a heavy motor could not be supported upon 35 a faucet and could not be conveniently attached thereto or detached therefrom. The invention is very simple, portable and, in or-

dinary size, does not weigh more than two or three pounds.

What I claim is:—

1. A water motor comprising a casing, a shaft journaled in said casing projecting therethrough, a rotor within said casing fixed to said shaft, a bearing block shiftably mounted upon said casing, a driven shaft 45 journaled in said block, and gears fixed to said rotor shaft and driven shaft for transmitting the rotation of said rotor to said driven shaft.

2. In a water motor according to claim 50 1, said bearing block being shiftable around the axis of said rotor shaft.

3. A water motor comprising a casing, a shaft journaled in said casing projecting therethrough, a rotor within said casing 55 fixed to said shaft, a support upon said casing having an arc-shaped dove-tailed extension, a bearing block having a dove-tailed groove in engagement with said dove-tailed extension, said block being shiftable upon 60 said support and the center of said arc-shaped dove-tailed extension coinciding with the longitudinal axis of said rotor shaft, a driven shaft journaled in said block, and gears fixed to said rotor shaft and driven 65 shaft for transmitting the rotation of said rotor to said driven shaft.

Signed at Buffalo, in the county of Erie, and State of New York, this 9th day of October, 1919.

PAUL EGEDI.
